(57) CLAIM

The ornamental design for a full face mask, as shown and described.

DESCRIPTION

FIG. 1 is a perspective view of a full face mask showing my new design, shown with a low-profile connector;
FIG. 2 is a perspective view of a second embodiment of a full face mask showing my new design, with a female connector;

FIG. 3 is a side elevation view thereof;

FIG. 4 is a top plan view thereof;

FIG. 5 is a bottom plan view thereof;

FIG. 6 is a end elevational view thereof;

FIG. 7 is a lower perspective view thereof;

FIG. 8 is a side elevation view thereof, taken for the opposite side of FIG. 3; and,

FIG. 9 is a bottom plan view thereof.
